UNITED STATES PATENT OFFICE

WILLIAM BLASKEWITZ, OF DETROIT, MICHIGAN, ASSIGNOR, BY MESNE ASSIGNMENTS, TO CLAYTON & LAMBERT MANUFACTURING COMPANY, OF DETROIT, MICHIGAN, A CORPORATION OF DELAWARE

FIRE POT CONSTRUCTION

Application filed December 10, 1928. Serial No. 324,907.

This invention relates to fire pot construction, and has to do particularly with that type of fire pot having a top plate, a fuel tank, a coil burner, and a shield surrounding the burner and positioned between the top plate and fuel tank.

Primarily due to the formation of carbon, it has been necessary with fire pots of the type above described to remove the burner after a period of operation for either replacement or repair. Such coil burners have included a preheating coil and a burner element, and various arrangements of such elements have been designed in an effort to permit easy removal of the burner without materially affecting the compactness and strength of the fire pot as a unit. One type of such fire pot structure is illustrated in the patent to Horn No. 1,469,598 of October 2, 1923, and another type of construction is illustrated in the application of Otto J. Groehn No. 640,191, filed May 19, 1923, now Patent No. 1,701,180, February 5, 1929.

The present invention relates to certain improvements in fire pot construction and shield structure over the prior art, particularly as set forth in the above mentioned patent and application. One of the important objects of the present invention resides in a shield which is positively clamped between the top plate and a cup structure supported on the fuel tank, together with a single-piece door which is hinged to the shield proper in a novel manner, and which is also adapted to be held in assembled relation to the shield structure in a novel manner.

Other features include the cup construction for receiving the lower end of the shield and the manner of forming the bottom part of the hinged door in cooperation with the novel form of cup member, whereby to positively prevent any fuel from being deflected or passing outside of the shield member.

In the drawings:

Fig. 1 is an elevation of a fire pot constructed in accordance with the present invention, and showing, in particular, the assembled position of the various parts.

Fig. 2 is a perspective view of the shield structure for same and illustrating the novel

manner of forming the co-operating hinge elements between the shield and the door.

Fig. 3 is a sectional view taken on line 3—3 of Fig. 2.

Fig. 4 is a sectional view taken on line 4—4 of Fig. 2.

Fig. 5 is a sectional view taken through the top plate of the fire pot and illustrating the manner of pinching the top of the shield whereby to positively fix the same against rotation while the fire pot remains in assembled relation.

Fig. 6 is a sectional view taken on line 6—6 of Fig. 5 and showing the V-shaped projections for pinching and clamping the top of the shield.

Fig. 7 is a sectional view taken through the bottom part of the shield and the cup showing, in particular, the formation of the bottom of the hinged door and the upper annular edges of the cup.

The main parts of the fire pot structure are best illustrated in Fig. 1, wherein 1 represents the combined tank and base, 2 the top plate, and 3 the shield which is clamped between the top plate and the base. The clamping of the shield is not directly between the top plate and the base but is specifically between the top plate and a cup member 4 which is supported and positioned by a spider 5 welded or otherwise secured to the top of the tank.

This clamping of the shield member 3 between the top plate and the cup insures a very strong and rigid casing for protecting the coil burner, and such rigid construction is in direct contrast with shield structures which are merely suspended to one member, such as the top plate and do not have any support or reinforcement for the other end. The clamping of the shield member is, of course, accomplished by tightening of the bolts on the ends of the rods 6, but it will be obvious that many blows may be accidentally received by the shield member, and that the reinforcing and clamping of the same will effectively protect the coil burner.

The coil burner may be generally designated 7 and is preferably connected to an upstanding conduit 8 which in turn is con-

nected to a suitable valve 10 by means of the union 11. To provide for removal of the entire burner unit, including the coil burner 7 and the conduit 8, I have provided a hinged door 12 which is secured to the remainder of the shield in a novel manner.

This door 12 is preferably slotted as at 13 to receive similarly positioned lugs 14 which are rolled over, as best shown in Fig. 3, to 10 form a hinged member or eye surrounding the portion of the door between the slot 13 and the edge thereof. In other words, the pin for hinging the door is merely a portion of the door itself and the hinge for receiving the pin is merely formed by a bent 15 over portion of the shield body.

The hinged door 12 is adapted to be held in closed position by means of a lug 15 stamped out of the shield member and bent 20 upwardly and outwardly at substantially right angles to the normal of the shield at that point. This lug is so stamped out as to extend upwardly and outwardly at an angle when it is bent out at right angles to the 25 shield, as best shown in Fig. 2. The slots 13 are preferably longer than the hinged members 14 whereby the door may be slightly lifted when it is closed, whereby the slot 16 in the door may cooperate with the lug 15 of the shield body. However, the lug 15 30 is preferably so positioned as to present the face 18 which is adapted to frictionally engage portions of the slot 16 so as to hold the door closed by reason of the friction between the parts.

35 The cup 4 is preferably fabricated so as to present an annular ring 19 and an annular upstanding flange 20, the flange 20 extending upwardly to a greater height than the ring 19. The lower edges of the shield body 40 fit in the groove between the annular ring 19 and the upstanding flange 20, but the door 12 is preferably shorter than the shield body, as best shown in Fig. 2.

45 A portion of the lower edge of the door is preferably turned inwardly at the bottom so as to form a horizontal inwardly extending flange 21, which is so positioned as to just barely clear the upper edge of the 50 flange 20. It will thus be seen that any liquid fuel forced from the burner in starting the apparatus and striking the hinged door will be positively prevented from flowing or dripping outside of the cup and onto the top of 55 the tank 1.

The lower edge of the main body of the shield fitting in the upper groove of the cup 4, it will be obvious that any liquid fuel flowing down the inside of the shield will be 60 collected by the cup. As the outlet from the burner element is usually directed upwardly it will be obvious that without these positive arranged elements that it will be very easy 65 for some of the liquid fuel to flow or drip 70 on to the fuel tank.

The hinged door 12 is also provided with a suitable stamped out handle 22 which makes it easy to open the door 12 to permit removal of the burner structure. It will furthermore be obvious that the pinching of the shield 70 member to prevent rotation of the same will insure maintenance of the door 12 in same position whereby the burner structure may always be easily removed. The top loop connecting the coil burner with the upstanding 75 conduit 8 is normally adapted to fit within a suitable opening formed by cooperating cut away parts 23 and 24 in the shield and door respectively.

It will thus be obvious that I have provided a shield member of very compact simple and novel construction and which is so adapted to be clamped between the top plate and the base of the fire pot as to greatly reinforce the fire pot structure as a whole, in 80 addition to serving as a spacing means between the top plate and the fuel tank, the fabrication of the shield and door members being such that the hinging and closure retainer means are fabricated from the members themselves whereby to present an extremely simple, inexpensive and efficient arrangement.

The shield is clamped between the top plate 2 and the cup member 4. The top plate 2 85 has a circumferential groove 30 (Figs. 5 and 6) which contains the spurs 31 which are arranged to dig into the upper edge of the burner shield 3 to hold the same non-rotatively.

100 What I claim is:

1. In a fire pot, a tank, a top plate, a cup member positioned at the top of said tank and provided with an annular groove at its upper edge, a burner positioned between the top plate and said cup member, and a shield surrounding said burner and spacing the top plate from said cup member, the lower edge of a portion of said shield fitting in the said groove in the cup member, and said shield being clamped between the top plate and cup member by clamping means directly connecting the tank and top plate, a portion of said shield member being of less height than the remainder of the shield and being hinged to the shield body whereby to permit removal of the burner laterally through the shield without disturbing the remaining elements of the fire pot.

115 2. In a fire pot of the class described, a tank, a burner, a top plate having a groove formed in the lower surface thereof, a cup supported on the tank and having a groove formed in the upper surface thereof, the outer edge of said groove being higher than the inner edge, and a shield member surrounding the fire pot burner and clamped between the top plate and tank whereby a portion of said shield member fits in the respective grooves of said top plate and cup 120 125 130

member, means formed in said top plate for gripping the upper edge of said shield when the parts are assembled whereby to prevent rotation of said shield, and a hinged door 5 completing the contour of said shield and being of less height than the shield body proper whereby it may swing freely.

3. In a fire pot of the class described, a tank, a burner, a top plate having a groove 10 formed in the lower surface thereof, a cup supported on the tank and having a groove formed in the upper surface thereof, the outer edge of said groove being higher than the inner edge, and a shield member sur- 15 rounding the fire pot burner and clamped between the top plate and tank whereby a portion of said shield member fits in the re- spective grooves of said top plate and cup members, means formed in said top plate for gripping the upper edge of said shield 20 when the parts are assembled whereby to prevent rotation of said shield, and a hinged door completing the contour of said shield and being of less height than the shield body 25 proper whereby it may swing freely, the lower edge of said door being bent inwardly to provide a flange which extends past the outer portion of the groove in said cup member, whereby to deflect any liquid fuel 30 hitting the door downwardly into the cup member.

In testimony whereof I affix my signature.
WILLIAM BLASKEWITZ.
